UNITED STATES PATENT OFFICE

153,235

DESIGN FOR A SHOESHINE BOX

Murray I. Pressberger, Brooklyn, N. Y.

Application June 21, 1946, Serial No. 130,901

Term of patent 3½ years

(Cl. D58—12)

To all whom it may concern:

Be it known that I, Murray I. Pressberger, citizen of the United States, residing at Brooklyn, New York city, in the county of Kings and State of New York, have invented a new, original, and ornamental Design for a Shoeshine Box, of which the following is a specification, reference being had to the accompanying drawing, forming part thereof.

Fig. 1 is a perspective view of a shoeshine box showing my new design.

Fig. 2 is a top plan view, and

Fig. 3 is a side elevational view thereof.

I claim:

The ornamental design for a shoeshine box, as shown.

MURRAY I. PRESSBERGER.
